CONNECTER SWITCH

Filed Dec. 12, 1927

UNITED STATES PATENT OFFICE

Victor S. Tharp, of Elmhurst, Illinois, assignor to Reserve Holding Company, of Kansas City, Missouri, a corporation of Delaware

CONNECTER SWITCH

Application filed December 12, 1927. Serial No. 239,384.

This invention relates in general to switches for telephone systems, and is particularly concerned with the provision of a new and improved rotary connecter switch, 5 which may be considered as an improvement on the switch shown in the application of R. Stehlik, Serial No. 40,239, filed June 29, 1925, now Patent No. 1,716,986, June 11, 1929.

10 More specifically, an object of the invention is to provide a rotary connecter switch having both directive and automatic primary or vertical movements, and having both directive and automatic secondary or rotary movements, wherein the switch rotates over successive levels in search of an idle trunk.

The provision of a connecter having the foregoing characteristics makes it possible to form large groups of trunks by combining 20 two or more levels, or by combining one or more levels with a portion of an adjacent level.

The means whereby the foregoing as well as other objects of the invention are attained 25 is pointed out in the specification taken in conjunction with the drawing forming a part thereof.

In the drawing, Fig. 1 shows the circuit arrangement whereby the various features 30 are attained. Fig. 2 is a fragmentary view showing the eleventh step rotary contacts.

The rotary connecter H is one of a plurality of similar switches which are accessible to selector switches, and is of the well 35 known Strowger vertical and rotary type. The connecter carries the usual line wipers and in this case two test wipers, one of which is the usual private wiper and the other is a special wiper. The first special wiper contact of each group of trunks leading to the 40 same subscriber's station is permanently grounded, the intermediate contacts of the group have neither battery nor ground potential thereon. In the case of a subscriber 45 having but one trunk the special test contact is grounded. The contacts accessible in one level are shown. For the sake of illustration the lines accessible by way of the first three contacts have been put into one group, 50 the fourth line leads to a station having but

one line, and the remaining lines are a portion of a different group. For illustrative purposes the first group of lines has been provided with an overflow metering arrangement. This may be omitted if desired. The 55 connecter may be seized by a selector switch and directly operated by means of impulses transmitted from a calling device to complete a connection with a desired subscriber such as the one shown at A. This 60 connecter is capable of automatically selecting an idle line in a group of lines leading to the same subscriber, and if all lines in the group are busy, of notifying the calling party of this fact. 65

The operations of the connecter H will now be explained in detail, and it will be assumed for this purpose, that a subscriber (not shown) desires to obtain a connection with a subscriber at A, and that the last two 70 digits of the subscriber's telephone number are 2-1, which indicates the position in the connecter of the first of three trunks leading to the desired subscriber's station. 75

When the connecter H is seized by a preceding selector over the trunk conductors 2-4, the line relay 10 operates over a loop (not shown) completed over the talking conductors 2, 4. The line relay 10 upon operating completes a circuit for the slow acting release relay 20, which relay at contact 21 places ground upon the release conductor 3 thereby establishing a holding circuit for the preceding switches, and at front contact 23 prepares the impulsing circuit. At contact 22 a circuit is established for the slow acting change over relay 30, said circuit extending from ground at contact 22, through the back contact 93 of relay 90, conductor 65, and closed double dog contacts DD to the 80 relay 30. 85

When the calling subscriber operates the calling device in accordance with the next digit in the called subscriber's telephone number a series of interruptions of the loop 95 circuit is produced, causing the line relay 10 to deenergize a plurality of times in accordance with the digit dialled. At each deenergization, an impulse of current is sent from ground at the back contact 12 to the

vertical magnet V. Upon the first operation of the vertical magnet the double dog springs DD open the initial energizing circuit for the relay 30, which relay being slow acting is maintained operated during the impulsive over a circuit extending through the front contact 31, back contact 11 which is closed every time the circuit of line relay 10 is opened, back contacts 53 and 93 to ground at front contact 22 of relay 20. The vertical magnet V operates to raise the switch wipers 110—113 step by step until they are opposite the desired level of bank contacts. At the end of the series of impulses, the circuit for the relay 30 is maintained open at the contact 11 and said relay releases. At contact 32 the impulsive circuit is switched to the rotary magnet. It may be mentioned at this time that the contacts DD are arranged on the switch in the manner shown in the patent to Martin No. 1,650,995, Nov. 29, 1927, differing therefrom in that here they are normally closed instead of being normally open.

The calling subscriber may now dial the final digit of the desired number. With each retraction of the armature 12 an impulse of current is sent to the rotary magnet over a circuit which extends by way of front contact 23, back contacts 58, 32, 57, 62, 56, winding of low resistance relay 70, back contact 97, to the winding of the rotary magnet. The rotary magnet and the low resistance relay 70 operate in series, and with each impulse the magnet moves the wipers 110—113, inclusive, over the bank of contacts in the selected level. The relay 70 being slow acting is maintained operated during impulsive and at contact 71 prepares a busy test circuit for the busy relay 80, and at contact 73 it bypasses the back contacts 56 and 62. It is assumed that the first three trunks in the level all extend to the same subscriber's station and only one impulse is sent to the rotary magnet. As stated before, the first contact in each group engaged by the wiper 111 has ground potential thereon, and therefore when the wiper 111 engages the contact 120 a circuit is established over said wiper to the upper winding of relay 50. Relay 50 is a two-step relay and when its upper winding is energized only the contact 55 closes. The slow acting relay 70 not having fallen back yet, the closure of the contact 55 is of no effect at this time. At the front contact 71 the busy test relay 80 is connected to the test wiper 112. If the first trunk is busy the test wiper 112 finds ground potential and before the relay 70 releases, the relay 80 operates from ground on said wiper. A moment after the cessation of the impulse, relay 70 releases. The relay 80 is maintained operated over a locking circuit extending through back contact 96, lower back contact controlled by the armature 71, front contact 81, inner contact of the rotary magnet, back

contact 63, conductor 74, outer contact of the rotary magnet, back contact 93, to ground at the front contact 22 of relay 20. At back contact 72 a circuit is established for the lower winding of the relay 50, said circuit extending through the lower winding of said relay, front first step contact 55 and lower back contact controlled by armature 53, back contact 72, front contact 83 to ground conductor 74. The lower winding of relay 60 is energized in parallel with the lower winding of relay 50. The relay 50 upon fully operating establishes a locking circuit for itself, said circuit extending through its lower winding, front contacts 55 and 53, to ground by way of back contact 93. At contact 59 a holding circuit for relay 80 is established independent of contact 63. The relay 60 upon operating establishes a holding circuit for itself at front contact 63. The following stepping circuit is now completed for the rotary magnet: battery, winding of the rotary magnet, contact 97, front contacts 82, 56, 62, 57, back contact 32, front contact 58, back eleventh step rotary contact, to grounded conductor 65. The rotary magnet moves the wipers 110—113 one step, and near the end of its stroke its contacts break the circuit for the relay 60 which relay releases and thereby opens the rotary magnet circuit. The rotary magnet releases and again completes a circuit for the relay 60 which relay again establishes a circuit for the rotary magnet. The slow acting relay 80 does not release during the short interval that its circuit is open at the rotary magnet contacts. The alternate energization of the relay 60 and the rotary magnet continues until either the switching relay 90 operates over wiper 112 when an idle trunk is found, or until the wiper 111 finds ground potential indicating that the last trunk of the group has been reached and is busy, or that the first trunk in the next group has been reached. Assume that the third trunk of the group is idle. When the third trunk is reached, wiper 112 receives battery potential from the line switch, and when the relay 60 releases, a circuit is established for the upper winding of relay 90, said circuit extending from battery at the wiper 112, through the back contact 71, upper winding of relay 90, back contact 61, front contact 52, upper winding of relay 60, back contact 93, contact 22, to ground. The relay 90 upon operating establishes a locking circuit for itself, through its lower winding. The relay 60 is differentially wound and does not operate over its upper winding, the same being provided to prevent the operation of the relay over the lower winding in the event the rotary magnet should restore its contacts before the relay 90 has had time to operate. The relay 90 opens the rotary magnet circuit and also the circuit for relays 80 and 50, places guarding ground

potential upon the wiper 112, and switches through the talking conductors. When the metering arrangement is provided, a high resistance relay 122 is connected to the last contact of each group engaged by the wiper 112 and when ground potential is placed upon the contact, relay 122 operates and connects the grounded low resistance marginal relay 123 to the contacts engaged by the wiper 111. The relay 123 does not operate, its circuit being open at the contact of the switching relay 90. The overflow meter OFM is not operated at this time. Upon the operation of the relay 90 ringing current is intermittently transmitted from the ringing equipment E through the upper winding of the relay 40 to the called station. At contact 91 a ring back tone is applied to the upper incoming talking conductor of the connector. When the called subscriber answers, a direct current circuit for the ring-cut-off relay 40 is completed over the called line loop. Relay 40 upon operating establishes a locking circuit for itself by way of its lower winding, cuts off the ringing current, and completes the talking connection. The usual back bridge relay is provided.

When the conversation is finished, both subscribers replace their receivers. It will be assumed that the calling subscriber replaces his receiver first. The line relay 10 releases immediately and opens the circuit of the slow acting relay 20. Before the release of relay 20, an impulse of current is sent to the slow acting relay 70, as follows: ground at back contact 12, front contact 23, back contacts 58, 32, 57, 62, and 56, through the winding of relay 70 to battery by way of front contact 97 of relay 90. The operation of slow acting relay 70 is at this time of no effect. A moment later slow acting relay 20 releases and at contact 21 removes ground from the release trunk conductor 3, thus allowing the preceding switches to release. The opening of the contact 22 is of no effect at this time, said contact being shunted by the front contact 5 of relay 1. Upon the release of relay 20 the circuit for the relay 70 previously traced is opened at the contact 23 and a moment later the relay 70 releases. Upon the release of relay 70 ground is again placed upon the release trunk conductor 3 thereby guarding the connector against seizure until such time as the called party shall have replaced the receiver, said ground extending from the front contact 95 of relay 90, through the back contact 71, upper winding of relay 90, back contacts 61 and 52, to conductor 3. When the called subscriber at A replaces his receiver, the back-bridge relay 1 releases and at contact 5 opens the holding circuit for the lower winding of relay 90, thereby allowing that relay to release, and at its lower back contact completes a circuit for the release magnet. The

connector is thus restored to normal by the last party replacing the receiver.

An explanation will now be given of the operation of the connector when all trunks in the called group are busy. As previously explained, the automatic rotary trunk hunting movement of the switch was obtained by the alternate operation and release of relay 60 and the rotary magnet, this action being stopped upon the operation of the relay 90, which relay operates from battery over the wiper 112 when said wiper comes upon an idle trunk. As was previously explained, when the last trunk of a group is seized, the relay 122 places ground through the low resistance marginal relay 123 upon the contact engaged by the wiper 111. It is to be remembered that during the automatic rotary motion of the switch the relays 50 and 80 are locked in their operated positions, and that just prior to the opening of the contacts on the rotary magnet, the relay 60 was in its operated position. Near the end of its stroke the rotary magnet opens the initial circuit for the relay 60. The relay 60 is now maintained operated over a circuit through the lower winding of the relay, back contact 72, front contact 63, front contact 51, contact 94, the wiper 111, to ground at the marginal relay 123. The marginal relay 123 operates in this circuit to operate the overflow meter OFM. The relay 60 maintains the rotary magnet operated. After a short interval of time the relay 80 releases, its circuit being maintained open at the contact of the rotary magnet. At contact 82 the relay 80 opens the circuit for the rotary magnet and the magnet releases. The original holding circuit for the lower winding for relay 60 is again completed by way of the back contact of the rotary magnet to ground at contact 22 of relay 20. The rotary magnet is now prevented from operating because of the open contact 82 of relay 80, and the relay 60 is maintained operated independent of the wiper 111. The busy tone will now be given to the calling subscriber by way of the busy tone machine B, back contact 84, and front contact 64. When the calling subscriber restores his receiver the relays 10 and 20 release in succession and open the circuit for the relays 50 and 60 and establish a circuit for the release magnet. The connector is thereby restored to its initial position.

The overflow metering arrangement including the relays 122 and 123 may be dispensed with if desired. In this case the last contact in a group of contracts engaged by the wiper 111 has neither battery nor ground potential thereon. In such a case if the last trunk in a group of trunks is busy the wiper 112 fails to find battery potential and the wipers 110—113 are stepped over to the first contact in the next group where the wiper 111 finds ground potential, and then re-

gardless of the busy or idle condition of this trunk the relay 60 is maintained operated over the wiper 111, thus preventing the relay 90 from operating over its upper winding, and when the relay 80 falls back a moment later the calling subscriber gets the busy signal in the manner pointed out before. When the busy metering scheme is dispensed with a relay such as relay 122 is connected to the 0-0 contact engaged by the wiper 112 and said relay places ground upon the 0-0 contact engaged by the wiper 111. This is provided for the purpose of stopping the switch when it reaches the very last switching position.

An explanation will now be given of the manner of operation of the connector in case a group comprising trunks in two or more successive levels is called. Upon being operated to the first trunk in the group and finding said trunk busy, the connector automatically rotates in search of an idle trunk in the manner previously pointed out. As previously pointed out the automatic rotary trunk hunting movement continues until it is stopped either by the operation of relay 90 from battery over the wiper 112 indicating that an idle trunk has been found or until relay 60 is maintained operated from ground over the wiper 111 indicating that the last trunk of the selected group has been reached and is busy, or that the first trunk in the succeeding group has been reached. Assume now that all the trunks of the group in the level are busy. Since it is assumed that the tenth trunk in the level is not the last trunk of the group the wiper 111 will not find ground when the tenth contact is reached, and since the wiper 112 fails to find battery the relay 90 will not be operated. The rotary magnet therefore takes an eleventh step. When this occurs, the projection 130 (Fig. 2) on the wiper shaft engages the spring 131, and moves the same a short distance. In its movement the spring 131 rides upon the upwardly dented portion 132 thereby forcing the spring 135 downward, and thus moving the upwardly bent portion 133 out of holding engagement with the spring 136, allowing the same to snap to the right and actuate its contacts. A circuit is established for the vertical magnet as follows (Figure 1): from battery through the vertical magnet, resistance 24, front eleventh step rotary contacts at spring 136 to grounded conductor 65. Simultaneous with the establishment of the vertical magnet circuit a circuit is established for the release magnet by way of the vertical off-normal contacts VON, back contact 33 and front contact at spring 131 to the grounded conductor 65. The switch commences to release. The release magnet causes the double-dog contact DD to close, thereby establishing a circuit for the slow acting relay 30, which

relay at back contact 32 maintains the rotary magnet circuit open. During the return to normal rotary motion of the switch the circuit for the vertical magnet is maintained partly energized through the resistance 24 which resistance is of such value that the vertical magnet barely moves its armature, the object of energizing the magnet at this time being to render it fast acting when its circuit is closed exclusive of the resistance. When the switch reaches the rotary normal position, the projection 134 (Figure 2) moves the spring 136 to the left, and said spring riding over the upward bent portion 133, forces the spring 135 downward. When the spring 136 rides past the bent up portion 133 the spring 135 again snaps upward and locks the spring 136 in position. When the contacts at 136 are restored to the position shown in the drawings a circuit for the vertical magnet independent of the resistance 24 is established, said circuit extending from the vertical magnet through front contact 32, front contact 58, back contact at 136, to grounded conductor 65. The vertical magnet operates before the switch can release vertically and raises the wipers 110-113 one step, at the same time opening the double-dog contact DD. This opens the circuit for slow-acting relay 30 which relay 90 a moment later releases, and at its contact 32 reestablishes the stepping circuit for the rotary magnet as previously traced. The rotary magnet takes one step and rotates the wipers 110-113 to the first contact in the bank. If the first trunk in the bank is busy, the rotary connector will automatically hunt for an idle trunk in this level in the manner previously pointed out. Since the switch is now in the same condition as it was in during the previous automatic trunk hunting movement, it may be seen that if an idle trunk is not found when the switch reaches the last trunk in the level, and if the wiper 111 does not find ground potential, the switch will restore in its rotary movement and repeat the same operation in the next level.

Should the connector H be operated by a calling subscriber to a trunk other than the first trunk of a group of trunks, as would be the case if a night number were called, the rotary connector acts as an ordinary connector and does not hunt for an idle trunk in the group. This may be seen from the following circuit arrangement: When the last impulse has been transmitted the slow acting relay 70 is in its operated position. The relay 50 is not operated at this time since there is no ground potential on wiper 111. If the called trunk is busy the wiper 112 finds ground potential and the relay 80 operates over a circuit previously traced. The relay 60 operates over its lower winding but does not complete a circuit for the ro- 130

tary magnet as before because the rotary magnet circuit is open at the contact 56 of relay 50. A moment later the slow acting relay 70 releases and opens the circuit for the slow acting relay 80 which a moment later also releases, its previously traced holding circuit being open at front contact 63. The relay 60 is maintained locked over a circuit extending through the back contact 72, front contact 63, to grounded conductor 74. The called party now receives the busy tone by way of back contact 84 and front contact 64. If the called line, upon which the wipers 110—113 came to rest were idle, the wiper 112 would not have found ground potential, hence the relay 80 would not have operated. A moment later, upon the release of relay 70, the relay 90 operates from battery over the wiper 112, back contact 71, upper winding of relay 90, back contacts 61 and 52 to the grounded release conductor 3. The relay 90 completes a locking circuit at its lower winding, and, as pointed out previously, switches through the talking conductors and completes the ringing circuit to the called line.

In compliance with the requirements of the patent statutes I have herein described a preferred embodiment of my invention. I do not, however, wish to be limited to the precise construction set forth, the same being shown for illustrative purposes only.

What I claim as new and desire to procure by Letters Patent is:

1. In a telephone system, trunks arranged in groups, a two-motion trunk hunting switch having access to said trunks, said switch including a group selecting magnet and a trunk selecting magnet, means for causing the switch to hunt for an idle trunk, said means including means for operating the group selecting magnet to select the groups one by one, means for directly operating the trunk selecting magnet to select the first trunk in the first group, means for automatically operating the trunk selecting magnet to hunt for an idle trunk in each group after the first as the group is selected, and means for stopping the hunting action of the switch responsive to an idle trunk being reached.

2. In a telephone system, a two-motion step-by-step trunk hunting switch having two operating magnets for operating the same in its two motions, respectively, means including one of said magnets for repeatedly operating the switch in one of its directions to its limit of motion and releasing the same, said action being automatically continuously repeated, means including the second magnet for preventing the complete release of the switch and for operating the switch one step in its other direction responsive to each release in the first direction, and means re-

sponsive to the finding of a desired trunk for stopping said switch.

3. In a telephone system, a multi-level trunk hunting switch, trunks accessible to said switch in each level, wipers for said switch, means for operating said switch responsive to two digits in a number to cause it to move said wipers in one level in search of an idle trunk, means effective upon said switch reaching its limit of motion for restoring said switch in said level, moving said switch to a different level, and repeating the motion in said different level, said movement automatically continuing from trunk to trunk and level to level, and means effective responsive to the wipers reaching an idle trunk for stopping the further trunk hunting movement of said switch.

4. In a telephone system, a vertical and a rotary multi-level trunk hunting switch, trunks accessible to said switch in each level, wipers for said switch, a rotary magnet and a vertical magnet for said switch, means for automatically operating the rotary magnet to move said wipers in one level in search of an idle trunk, means effective upon said switch reaching its limit of rotary motion for restoring said switch in said level, for partially energizing said vertical magnet to prevent restoration below said level, for operating the vertical magnet to move said switch to a different level, and for repeating the rotary motion in said different level, said action automatically continuing from trunk to trunk and level to level, and means effective responsive to the wipers reaching an idle trunk for stopping the further trunk hunting movement of the switch.

5. In a telephone system, a connector switch having a directive and an automatic primary movement and a directive and an automatic secondary movement, means for directly operating said switch in its primary movement and in its secondary movement successively, means effective under predetermined conditions responsive to the cessation of the directive movement for automatically operating said switch in its secondary movement, and means thereafter effective under predetermined conditions for continuing the operation of said switch in its automatic primary movement.

6. In a telephone system, a connector switch having a directive and an automatic primary movement and a directive and an automatic secondary movement, means for directly operating said switch in its primary movement and in its secondary movement successively, means effective under predetermined conditions upon the cessation of the directive movements for automatically operating said switch in its secondary movement, and means thereafter effective under predetermined conditions for continuing the operation of said switch in its automatic primary movement.

mary movement, and means thereafter effective for again automatically operating said switch in its secondary movement.

7. In a telephone system, a rotary connector, lines divided into groups and subgroups accessible to said connectors, some of said subgroups including lines in plurality of groups, a primary motor magnet for operating said connector in a primary movement to select a group in accordance with a digit of the called number, a secondary movement in accordance with another digit of the called number to select a desired subgroup, means for continuing the secondary movement to automatically select an idle line in the selected subgroup, and means effective if an idle trunk in the selected group is not found for causing the primary magnet to select a different group and repeating the automatic secondary trunk hunting movement of said switch.

8. In a telephone system, a rotary connector having a directive primary movement and a directive and automatic secondary movement, a test wiper, means controlled by the existence of a certain potential on the test wiper for instituting the automatic secondary movement of the switch, and circuit arrangements controlled by the recurrence of the same potential on the test wiper for stopping the switch.

9. In a telephone system, a rotary connector having a directive and an automatic primary movement, and a directive and an automatic secondary movement, a test wiper, means effective upon the termination of the directive secondary movement and controlled by the existence of a certain potential on the test wiper for instituting the automatic secondary movement of said switch, means controlled by the recurrence of the same potential on the test wiper for stopping the secondary automatic motion of the switch, and means effective if the said potential is not placed on the said wiper when the switch reaches its extreme secondary position for restoring the switch in its secondary motion, automatically operating the same in its primary motion, and then repeating the automatic secondary movement of the switch.

10. In a telephone system, a rotary connector having a directive primary movement and directive and automatic secondary movements, a test wiper, means controlled by the existence of a certain potential on the test wiper for instituting the automatic secondary movement, circuit arrangements controlled by the recurrence of the same potential on the test wiper for stopping the switch, an additional test wiper, and additional means controlled over the second wiper for stopping the automatic movement of said switch.

11. In a telephone system, a rotary connector having a directive primary movement

and directive and automatic secondary movements, a test wiper, means controlled by the existence of a certain potential on the test wiper for instituting the automatic secondary movement, circuit arrangements controlled by the recurrence of the same potential on the test wiper for stopping the switch, an additional test wiper, additional means controlled over the second wiper for stopping the automatic movement of said switch, and testing means for determining over which wiper the switch was stopped.

12. In a telephone system, a rotary connector having a directive primary movement and directive and automatic secondary movements, a test wiper, means controlled by the existence of a certain potential on the test wiper for instituting the automatic secondary movement, circuit arrangements controlled by the recurrence of the same potential on the test wiper for stopping the switch, an additional test wiper, additional means controlled over the second wiper for stopping the automatic movement of said switch, and means effective if the switch was stopped over one of said wipers for transmitting ringing current over the outgoing conductors of said switch and effective if the switch was stopped over the other of said wipers for transmitting busy signalling current over the incoming talking conductors of said switch.

13. In a telephone system, a rotary connector having a directive primary movement and directive and automatic secondary movements, a test wiper, means controlled by the existence of a certain potential on the test wiper for instituting the automatic secondary movement, circuit arrangements controlled by the recurrence of the same potential on the test wiper for stopping the switch, an additional test wiper, additional means controlled over the second wiper for stopping the automatic movement of said switch, said additional means being ineffective if said test potential recurs upon said first mentioned test wiper, and means effective if the switch was stopped over one of said wipers for transmitting ringing current over the outgoing conductors of said switch and effective if the switch was stopped over the other said wipers for transmitting busy signalling current over the incoming talking conductors of said switch.

14. In a telephone system, a step-by-step rotary connector having a directive primary movement and directive and automatic secondary movements, two test wipers, means effective under predetermined conditions for instituting the automatic secondary movement, means controlled over either wiper for stopping the automatic secondary movement, and means for testing over each of said wipers successively after each automatic step to determine if the stopping means shall be

effective, the second test being omitted if the stopping means is effective responsive to the first test.

15. In a telephone system, a step-by-step rotary connector having a directive primary movement and directive and automatic secondary movements, two test wipers, means effective under predetermined conditions for instituting the automatic secondary movement, means controlled over either wiper for stopping the automatic secondary movement, means for testing over each of said wipers successively after each automatic step to determine if the stopping means shall be effective, the second test being omitted if the stopping means is effective responsive to the first test, and signalling means effective in either of two different manners for indicating which of said two tests rendered said 20 stopping means effective.

16. In a telephone system, a rotary connector having directive primary movement and directive and automatic secondary movements, a group of trunks accessible to said connector, a test wiper, test contacts over which the wiper moves, the test contact of the first trunk of said group having a certain potential thereon, means controlled by the existence of said certain potential on 25 the test wiper for instituting the automatic secondary movement, means effective under predetermined conditions for placing said potential on the last contact of said group, and circuit arrangements controlled by the 30 recurrence of the same potential on the test wiper for stopping the switch.

17. In an automatic switch, an operating magnet and a release magnet, means for energizing said operating magnet to operate said switch, means for energizing said release magnet to restore said switch, and means for partially energizing said operating magnet to prevent the complete restoration of said switch.

45 18. In a two motion switch, a primary magnet and a secondary magnet, means including said primary magnet for operating said switch in its primary movement, means including said secondary magnet for operating said switch in its secondary movement, means for restoring said switch, and means including said primary magnet for preventing the restoration of said switch in its primary movement.

55 19. In a switch having vertical and rotary movements, a vertical magnet and a rotary magnet, means including said vertical magnet for operating said switch in its vertical movement, means including said rotary magnet for operating said switch in its rotary movement, means for releasing said switch, and means for partially energizing said vertical magnet during the rotary release of said switch to prevent the vertical 60 release of the switch.

20. In a vertical and rotary switch, means including a vertical magnet for operating said switch in its vertical movement, means including a rotary magnet for operating said switch in its rotary movement, means for releasing said switch operative when said switch reaches its limit of motion in its rotary direction, and means responsive to said releasing means for partially energizing said vertical magnet to prevent the release of said switch in its vertical direction.

In witness whereof, I hereunto subscribe my name this tenth day of December, A. D. 1927.
